UNITED STATES PATENT OFFICE

2,575,914

CONVEYER

Roger L. Griffin, Marblehead, and Norman Y. Moore, Danvers, Mass., assignors to A. C. Lawrence Leather Company, Peabody, Mass., a corporation of Maine

Original application March 23, 1944, Serial No. 527,706, now Patent No. 2,488,907, dated November 22, 1949. Divided and this application November 23, 1946, Serial No. 712,010

5 Claims. (Cl. 104—168)

1

The present invention relates to conveying apparatus and more particularly to an apparatus for conveying flat, rigid articles such, for example, as boards or plates upon which tanned skins are stretched for drying.

The object of the present invention is to provide a conveying apparatus of the above type in which the articles are propelled along the conveyor by power means occupying but a relatively short section of the conveyor, the other articles or boards on the conveyor being propelled by contact with one another from the board or boards being propelled directly by the power means.

Another object of the present invention is to provide a conveying apparatus in which the articles are propelled directly by the power means and independently of the supporting means.

Still another object of the present invention is to provide a conveying apparatus in which the flat, rigid articles are supported vertically and are propelled edgewise by power means engaging the bottom edges of the articles.

Another object of the present invention is to provide a conveying apparatus in which generally flat and rigid articles of varying thickness in different portions are propelled by power means which yieldingly engage opposite faces of the articles.

To the above ends the present invention consists in the devices and combinations of devices herein described and claimed.

In the accompanying drawings which illustrate the conveying apparatus shown and described in the applicants' co-pending application Serial No. 527,706, filed March 23, 1944, now Patent No. 2,488,907, dated November 22, 1949, of which the present application is a division, Fig. 1 is a side elevation of a complete conveyor for conveying plates for supporting tanned hides and skins and embodying the present invention, and Fig. 2 is a top plan view of the same; Fig. 3 is a side elevation of a portion of the conveyor showing one form of propelling or feeding mechanism for the plates, and Fig. 4 is a top plan view, and Fig. 5 a vertical transverse sectional view of the same looking from the right of Fig. 3; Fig. 6 is a side elevation, partly in section, and Fig. 7 a top plan view, partly in section on line 7—7 of Fig. 6, of another form of power feeding mechanism; Figs. 8 and 9 are details in side elevation and vertical transverse section, respectively, of the trolley or plate carrying devices; and Fig. 10 is a horizontal section on line 10—10 of Fig. 3 showing the

2

contact members or bumpers on the front and rear edges of adjacent plates.

The present invention, which is illustrated in the drawings as embodied in a pasting machine, 5 comprises a closed orbit conveyor system with overhead track and trolleys upon which the skin-receiving plates are permanently suspended. These plates are advanced by a power feed mechanism which operates directly upon the plates 10 and independently of the supporting means. The power feed mechanism operates upon never more than two plates at a time, but as these are propelled forwardly, they in turn propel by direct contact the other plates ahead of them carrying one plate after another through the washing, 15 drying and pasting units and past the skin-applying station.

From the skin applying station the plates are advanced by hand to the drier, through which 20 they are slowly passed under power, such advance being controlled by the operator at the discharge end of the drier who withdraws the plates, strips the dried skins therefrom, and returns them to the starting point, thus completing 25 the cycle of operation.

Referring to Figs. 1 and 2 of the drawings, which show more or less diagrammatically the complete system or apparatus, and assuming point 25 at the right hand end of the apparatus 30 as the starting point of the cycle, the plates 27, supported from the trolleys 29 on the overhead conveyor track 31, are advanced by hand to the power feed unit or station 33. Here they are engaged and supported at their bottom edges by 35 rolls driven by motor. Each board as it is advanced by the drive in turn engages the board just ahead of it and advances that board as well as all of the other boards through or past the washing unit 39, drying or squeegee unit 41, 40 paste applying unit 43, and the long skin-applying or stretching unit 45, which, as shown in Fig. 1, is of sufficient length to accommodate five plates, each carrying a pair of skins on each side.

As the plates with the pasted skins are discharged from the stretching unit 45, they are 45 pushed by hand along the short connecting section 59 of the conveyor, over the switch 61 and into the drier 63 where they are supported upon two conveyor tracks 65 and 67 transversely of the same in close relation.

The power drive 33 which advances the plates through the washing, drying, pasting and stretching stations, is shown in enlarged detail in Figs. 4 and 5, and comprises three V-grooved feed rolls 55 73, 75, and 77 mounted on shafts 78, 79 and 80,

respectively, supported in bearings 81 carried by the supporting plates 82 and 83. Feed roll 73 is loose upon shaft 78, but is arranged to be driven therefrom by a one-direction clutch comprising the ratchet wheel 74 fixed on the shaft and the cooperating pawl 76 pivotally mounted on the roll 73. Rolls 75 and 77 are fixed upon their respective shafts 79 and 89. These feed rolls engage the bottom edge of the plate, raising the latter slightly so that practically the entire weight is applied on the rolls, thus giving sufficient friction to insure proper advance of the plate supported thereon and also of the series of plates ahead and passing through the washing, drying, pasting and stretching stations or units.

The feed roll 73 is driven by the motor 84 which is provided with a variable speed driving pulley 85 and adjusting hand wheel 86, of usual and well known construction. A belt 87 transmits motion to the speed-reduction unit 88, and the sprocket and chain connection 89 to the shaft 78 of the feed roll 73. The feed roll 75 is in turn driven by the chain and sprocket connection 91 from the shaft 78 of the feed roll 73, and the feed roll 77 is driven by a supplementary chain and sprocket connection 93 from the shaft 79 of the feed roll 75.

The purpose of the ratchet and pawl drive from shaft 78 to feed roll 73 is to permit a plate to be advanced rapidly by hand while in engagement with only roll 73 of the feed unit to bring it into immediate contact with the next preceding plate while that is still being advanced by the unit, thus avoiding gaps or spaces between adjacent plates as they pass through the unit and the later temporary stoppage of the train or series of plates until the rearwardly-spaced plate then driven by the unit contacts the rear plate of the stationary series.

In order to insure the positive driving of the plate as it is leaving the feed unit, the supporting plates 83 for the rolls 75 and 77, are carried by a frame 94 pivotally mounted on the shaft 95 carried by the stationary members or lugs 97. Thus there will always be at least two of the rolls operating to drive the line of plates, as shown in Fig. 3, and for a part of the time all three rolls, so that continuous and uniform advance will be insured.

The plates as they enter the feed drive unit are guided at their front edge by converging guides 99 supported upon the posts 101 in position to engage the vertical portion of the metal molding strips 103, which cover the front or advancing edge as well as all other edges of the plate, and guide the bottom edge of the plate with its horizontal molding strip into the groove of feed roll 73 as shown in Fig. 5. As the plate engages the roll, the front end of the plate is slightly raised so that its weight is transferred from the trolley to the feed roll, thus insuring sufficient pressure to give positive and uniform feeding movement to the plate.

On leaving the roll 73 the front edge of the plate passes between the vertical guides 105, see Fig. 4, which guide the bottom of the plate to the second feed roll 75, the parts just before engagement being in the position shown in Fig. 3, with the front portion of the plate at that time supported by the trolley, and the rear portion by the roll 73. At this moment it will be noted that both plates shown in Fig. 3 are being driven by the feed rolls, the leading or left-hand plate by roll 77, and the following or right-hand plate by roll 73. As soon as the leading

edge of the following plate contacts the roll 75 and for a short time thereafter all three rolls will be driving, rolls 73 and 75 operating upon the following plate and roll 77 upon the leading plate, and then when the leading plate leaves roll 77, all three rolls operate upon the following plate alone. Finally this plate leaves the first roll 73 and for a time is driven by both rolls 75 and 77, while a third plate is engaged and driven by roll 73. Thus uniform feed of the work is assured, since never less than two of the feed rolls and some of the time all three rolls are in operative engagement with one or more of the plates.

In order to insure proper engagement or abutment of adjacent plates so that the leading plate may be advanced by the following plate, the leading and following vertical edges of each plate are provided with a rubber abutment member 107, see Fig. 3 and in enlarged detail Fig. 10. These members are attached to the edge of the plate and the molding 103 by means of the clamping screws or bolts 109. The contact faces of these abutment members are of sufficient width to insure engagement between the adjacent plates, and being of rubber, are noiseless in operation.

An alternate form of feed mechanism is shown in Figs. 6 and 7 wherein the co-operating pairs of hollow circular tubes or tires 110 and 111 are carried by the hubs 112 and 113 mounted upon the pairs of vertical shafts 114 and 115 supported upon the ball thrust bearings 117 in the bearing posts 119. One pair 114 of these vertical shafts is driven from the motor 121 through variable speed pulley 122, belt 123, counter shaft 125 and vertical shafts 127, with bevelled gearing 129 at the lower ends and spur reduction gearing 131 at the upper ends. The hubs for tires 110 are loosely mounted upon their shafts 114, while tires 111 are fixed upon their shafts 115.

The shafts 114 carry the ratchet wheels 134, and the hubs for tires 110 carry the pawls 135 to permit the hand advance of a plate past tires 110 as described in connection with a similar arrangement in the construction shown in Figs. 3, 4 and 5. The second pair 115 of shafts is driven through sprocket and chain connections 133 from the first mentioned pair 114.

The tubes or tires are inflated sufficiently to give the required driving pressure upon the opposite sides or faces of the plate, yet yield to permit the passage of the molding or binding 103 at the front and rear edges thereof. No guides are required with the modified construction, the tires themselves directing the plates to the position for engagement, and also maintaining them in proper vertical position in their passage through the feed unit.

The plates illustrated in the drawings are formed of sheet steel bound around their edges with a T-shaped metal protective strip 103, see Fig. 10. Spaced from the ends of the plates on the top edges thereof are the supporting clips 333 which pass around and beneath the side lips of the protective strip and are provided in their upper portion with an aperture 335 through which passes the S-shaped supporting link 337. The upper hook of this link engages the opening or eye in the depending member 339 of the trolley, which is provided with four wheels 341 rolling upon the spaced L-shaped rails or tracks 343 welded to the inverted U-shaped member 345 carried by the I beams 346 of the structure.

While the plates are not removed from their

trolleys at any point during their cycle of operation, nevertheless the links 337 permit easy disconnection in the event that, for one reason or another, it is desired to remove a plate for inspection or replacement. Furthermore, the double pivotal connection of the links 337 permits the slight vertical lifting of the plate when it engages the grooved rolls of the feeding mechanism, the trolley at such times being relieved of practically all the weight of the plate, which is now borne by the feed rolls, insuring steady and regular advance of the entire line of plates through the skin-applying station and intervening units.

In the operation of the conveyor above described, the plates remain suspended at all times upon the trolleys which travel upon the overhead rails around the closed orbit of the conveyor. The first step in their cycle of operations is the advancing by the operator to the feeding unit of a plate from which a dried skin has just been removed. From this point the plate is being advanced by the feed unit, first by direct contact therewith and then by the movement of the following plates as they each in turn pass through such feed unit.

After the plate leaves the feed unit it is carried through the washing unit where it is thoroughly cleaned by the constantly flowing jets of water and the rotating brushes. Next it passes through the drying unit where wipers or squeegees remove the water remaining on the surfaces, the wipers being automatically lifted to permit the passage of the rear and front edges of adjacent plates with their projecting molding or reinforcing strips.

The plate, still driven by the feed unit through the intervening plates, next passes the paste applying devices where both faces are given an even coating of paste by the vertically oscillating spray nozzles.

Finally the plates are carried past the skin-applying station and positions, of which five are shown in the drawings, where pairs of operatives standing on opposite sides of the plates apply and stretch the skins, a part at a time, until the entire skin is stretched out on the plate.

As soon as the final stretching is completed, the plates are propelled to the tunnel drier through which they are advanced by a separate and independent power drive at a relatively low rate of speed while held in closely spaced, transverse arrangement.

In the conveyor herein shown and described, the power means for propelling the plates occupies but a small portion of the operative length of the conveyor, thus simplifying the installation and reducing its cost. Furthermore, the application of the power drive directly to the plates avoids the necessity of long conveyor chains and reduces power consumption and the likelihood of stoppages from breakdowns.

Where the plates are fed by engagement of the power drive mechanism with the bottom edge of the plates, as shown in one specific form, the wear is taken by the heavy reinforcing strip, and where pneumatic tired feed wheels are employed, as shown in another specific form, the latter will automatically permit the passage of the laterally projecting vertical strips on the front and rear edges of the plates.

Where in the claims the term plates is used, this is to be understood as not limited to the leather drying plates specifically shown and described herein, but includes any articles and

constructions which are adapted to be suspended from conveyor trolleys and to be advanced by direct contact of their bottom edges or side faces with power driven feed rolls.

5 Nor is the invention to be limited to the specific constructions and arrangements herein shown and described, but may be embodied in other constructions and arrangements within the scope of the language of the claims.

10 Having thus described the invention, what is claimed is:

15 1. In a conveyor system of the type having an overhead track, trolleys thereon, and plates suspended from the trolleys, power driven feeding means for advancing the plates along the track, said means comprising three power driven rolls positioned beneath the track in the line of feed of the plates to engage the bottom edge of a suspended plate to advance the same, and an over running clutch to permit free rotation of the first roll in the line of feed at a speed in excess of the driven speed of the two rolls, the two other rolls being mounted in a frame pivoted midway the rolls upon a horizontal axis transverse to the line of feed.

20 2. In a conveyor system of the type having an overhead track, trolleys thereon, and plates suspended from the trolleys, power driven feeding means for advancing the plates along the track, said means comprising two pair of power driven rolls each provided with pneumatic tired peripheries and mounted to turn upon vertical axes, the rolls of each pair being positioned opposite one another to engage opposite faces of a plate to advance the same, and the pairs being spaced in the direction of the feed of the plates a distance less than the horizontal length of a suspended plate, the first pair of rolls being driven through an over running 25 clutch to permit free rotation of said rolls in excess of the driven speed of the second pair of rolls.

25 3. In a conveyor system of the type having an overhead track, trolleys thereon, and plates suspended from the trolleys to move edgewise along the conveyor, mechanism for driving said plates comprising driving rolls spaced from one another in the direction of travel of the plates a distance less than the horizontal length of a suspended plate, said rolls being arranged to engage said plates and advance them along said conveyor in end-to-end relation, driving means for rotating each roll, and an over-running clutch between said driving means and the first roll in the line of feed operative to permit free rotation of said first roll at a speed in excess of the driven speed of the rolls.

4. In a conveyor system of the type having an overhead track, trolleys thereon, and plates suspended from the trolleys to move edgewise along the conveyor, mechanism for driving said plates comprising two pairs of driving rolls, each pair being spaced apart in the direction of travel of the plates a distance less than the horizontal length of a suspended plate, the driving rolls of each pair being arranged to engage the opposite faces of the suspended plates and advance them along said conveyor in end-to-end relation, and means for driving at least one roll of each pair.

5. In a conveyor system of the type having an overhead track, trolleys thereon, and plates suspended from the trolleys to move edgewise along the conveyor, mechanism for driving said plates comprising two pairs of driving rolls each

pair being spaced apart in the direction of travel of the plates a distance less than the horizontal length of a suspended plate, the driving rolls of each pair having pneumatic tired peripheries and being mounted to turn on vertical axes so as to engage the opposite faces of the suspended plates and advance them along said conveyor in end-to-end relation, and means for driving at least one roll of each pair.
